Specification for Design.

Patented Feb. 24, 1914.

Application filed December 21, 1912. Serial No. 738,076. Term of patent 14 years.

To all whom it may concern:

Be it known that I, HERBERT M. DAWLEY, a citizen of the United States, residing at Buffalo, in the county of Erie and State of New York, have invented a new, original, and ornamental Design for a Combined Mud-Guard and Headlight-Casing for Vehicles, of which the following is a specification.

In the accompanying drawing Figure 1 is a side elevation of a combined mud guard and head light casing showing the design. Figs. 2, 3 and 4 are respectively a plan, front elevation and rear elevation thereof.

The characteristic feature of this design

consists in providing a mud guard with a forwardly enlarging or trumpet-like hollow protuberance or head light casing A which projects forwardly and upwardly from the downwardly curved front portion of the mud guard.

I claim:

The ornamental design for a combined mud guard and head light casing for vehicles, as shown and described.

HERBERT M. DAWLEY.
